LIGHT TABLE

Alex J. Weinstein, Mount Vernon, N.Y., assignor, by mesne assignments, to The Edna Lite Corporation,
Peeckskill, N.Y., a corporation of New York

Filed Oct. 2, 1962, Ser. No. 71,954

Term of patent 14 years

(Cl. D57—1)

FIG. 2.

FIG. 1.

FIG. 1 is a perspective view of a light table embodying my new design; the electric cord member is fragmentarily shown for ease of illustration;

FIG. 2 is a side elevation thereof; the opposite side being a mirror image of the side shown; and

FIG. 3 is a top plan view thereof; the conventional cord member is broken away to indicate indeterminate length.

The broken lines are shown for illustrative purposes only.

I claim:

The ornamental design for light table, substantially as shown and described.
